UNITED STATES PATENT OFFICE.

LORENZO LANE AND LAURIN D. WOODWORTH, OF YOUNGSTOWN, OHIO.

MOLD FOR ROOFING-TILES.

SPECIFICATION forming part of Letters Patent No. 279,402, dated June 12, 1883.

Application filed November 17, 1882. (No model.)

To all whom it may concern:

Be it known that we, LORENZO LANE and LAURIN D. WOODWORTH, both citizens of the United States, residing at Youngstown, in the county of Mahoning and State of Ohio, have invented certain new and useful Improvements in Molds for Tiles for Roofs, &c.; and we do hereby declare the following to be a full, clear, and exact description of the invention, such as will enable others skilled in the art to which it appertains to make and use the same.

Our invention relates to improvements in glass molds used for the manufacture of tiles; and the object is to construct a glass mold for tiles that is very simple in its construction, reliable at all times, and not liable to get out of order, and by which an ornamental tile can be manufactured that forms a perfect waterproof roof.

The invention consists in forming the mold of a matrix or base-section, upon which a ring fits, and a plunger. In the base the contour of the tile is partly contained with a flange, and the surface is formed with two or more transverse curves or angles and preferably a series of perpendicular corrugations. The ordinary top ring, fitting on said base, serves to arrest the flow of glass upward, and gives form to the upper edge of the tile. The plunger is provided on its face with a series of inclined corrugations counter to the perpendicular corrugations on the upper face, and has two or more curves or angles to coincide with those of the face of the base and the thickness of the tile added thereto.

It also consists in the construction and arrangement of certain parts, as will be more fully described hereinafter and more specifically pointed out in the claims, reference being had to the accompanying drawings and the letters of reference marked thereon.

Like letters of reference indicate like parts in the different figures of the drawings, in which—

Figure 1 represents a plan view of the base of the mold. Fig. 2 is a plan view of the top ring. Fig. 3 is a plan view of the plunger, showing its face. Fig. 4 is a longitudinal vertical section of the mold with a tile in place. Fig. 5 is a cross-section of the same on line *x* *x*. Fig. 6 is a plan view of a base of a mold

for the half-tiles. Fig. 7 is a similar view of the top ring for the same. Fig. 8 is a plan view of the plunger for the same. Fig. 9 is a 55 cross-section of this mold on line *y* *y*. Fig. 9^a is a side view of the tile formed in this mold. Figs. 10, 11, and 12 are plan views of the base, top ring, and plunger of a mold for the 60 combination tiles.

In the accompanying drawings, A is the base or mold plate of the mold, having on its face two or more curves or angles, *a*, and a series of perpendicular corrugations, *b*. The upper flange of the tile is formed in the depression or recess *e*, and is provided with an extension, *d*, at the center, while the lower flange is formed in a depression, *e*, and has a similar extension, so that the two overlap each other at the sides, and at the same time form 70 abutting edges when two adjoining tiles are brought together. The upper and lower ends *f* *g* are rounded, and form cup-shaped depressions, so that when two or more tiles are brought together at these points they fit over 75 the extensions on the sides and form a perfectly water-tight joint. The base is provided with recesses *h*, into which lugs *i* on the top ring, B, fit when the two are brought together, and serve to hold them in place. This ring is 80 curved or angled on its face to coincide with the curves or angles on the base. The base or mold plate, as well as the top ring, is provided with the usual handles, C D, for manipulating them. On the rear side of the top ring are 85 arranged suitable lugs, by which it receives the ordinary pressure to keep the ring in place while the plunger is passing through it. The plunger or follower E has the ordinary neck or projection, *e*, for securing it to the press. 90 Said plunger is preferably provided on its face with a series of corrugations, *k*, arranged at an angle or counter to those in the base, so that when the tile is finished the rays of heat and light will be scattered and diffused by said 95 corrugations. In the flanges at the side abutting edges is formed a semicircular indentation, *m*, having an enlargement, *n*, at its upper side, so that when two tiles are laid together a complete hole is formed for a nail, screw, or 100 bolt. We prefer to place these holes so far above the central transverse line that the nail will escape the rounded end *f*.

The mold shown in Figs. 6 to 9 is similar in

all respects to that shown in preceding figures, excepting that this mold is intended for the gable or side tiles, and has a flange, *l*, (shown in Fig. 9^a.) on its side, which is to form the joints at the sides of the roof or siding. These tiles must be made right and left.

The mold shown in Figs. 10, 11, and 12 is similar in all respects to that shown in the preceding figures, excepting that this mold is intended for the comb-tiles, or those intended for the upper edge of the roof, and it is extended at its upper side, *o*, above the nail-hole, and has a flange, *p*, against which the combing is fitted. The rounded cup-shape end is arranged at the bottom of these tiles.

The mold for making the tiles for the eaves is similar to that for forming those of the comb, excepting that the extension *o* and the flange *p* are dispensed with and the rounded cup-shape end is formed at the top instead of at the bottom.

It will be readily understood that all of these tiles can be employed to cover the sides of a building just as well as the roof.

25 These molds can be also made in a similar manner for the manufacture of hip and valley tiles, the base, top ring, and plunger being then changed to conform to the contour of such tiles, with the necessary depressions or recesses for forming the necessary flanges and depressions on the tiles. The curves or angles in the tiles must be always equal, so that in laying them they will exactly fit over each other.

35 The operation is as follows: The plunger is attached to the press, the mold with the ring in place is brought directly underneath, and when the proper gather of glass is dropped into the mold and cut off, the plunger is made 40 to descend into the ring far enough to cause the glass to spread throughout the matrix, thus forming the tiles with the flanges and corrugations. The plunger is then raised, the ring removed, and the tile emptied from the 45 mold and taken to the oven or layer for tempering, &c.

The advantages in manufacturing tiles in the different molds described, which usually embrace seven molds for the different tiles, are 50 as follows: A glass roof can be formed absolutely storm and weather proof without the use of putty, cement, or other material. The curves or angles enable the roofer to fit the tiles with a perfect joint at all points, the lower 55 part of the tile (as it lies in the roof) covering the upper parts of the two lower tiles with the interlocking flanges. By the flattened sides of the matrix the flanges of the tile are extended beyond the central transverse line, 60 thus overlapping each other upon opposite sides, adding strength to the tiles, as the ends of the said flanges, when the tile is in place, rest in the cups formed by the rounded ends, and are covered by a similar cup formed 65 by the opposite rounded end, thus entirely concealing the joint and making it waterproof. The nail, screw, or bolt is likewise

concealed and covered by this joint. A covering of glass which as a whole will endure disturbances of the surface upon which it is 70 laid without injury. The use of a round bevel-headed nail, screw, or bolt slightly smaller than the hole permits the two adjoining tiles to be moved up or down slightly, or for a limited distance, so that the adjacent parts 75 fall away from the nail, screw, or bolt, whereby no binding occurs resulting in fracture. The tiles made in our molds rest equally upon the surface below at all points of pressure, so as to overcome the leverage occurring in 80 ordinary tiles, subjecting them to breakage by light pressure or concussion at the parts not resting on the surface below. The curves produce an air-tight chamber useful in repairing. The tiles, having the counter corrugations, cause the light to be diffused, while cutting off the direct rays of the sun, thus forming a much cooler glass roof and siding 85 than any other known to us. This is caused by the corrugations on the upper and lower surfaces being arranged as shown, by which the 90 heat and light rays, which go together, are scattered. The roofing or siding can be easily and readily repaired in case of breakage. The flanges form a perfect finish at the gables, 95 covering all spaces caused by curvatures of the tile. By these molds hip and valley tiles may be formed at any angle, the tiles for this purpose being readily trimmed on one of their edges to suit the different angles. The 100 tiles may be made of any color or shade, and a beautiful appearance thus given to the roof or siding. The corrugations also prevent the warping of the tiles in process of annealing.

We are aware that molds with rings and 105 plungers are made for the manufacture of various articles of glassware, the shape of which is imparted to them by the form of the matrix, combined with the form and operation of the ring and plunger, and we disclaim such molds, 110 broadly; but,

Having thus described our invention, what we claim, and desire to secure by Letters Patent, is—

1. In the manufacture of tiles, the mold-plate 115 herein described, provided with two or more transverse curves or angles on its face and suitable flange depressions, substantially as specified.

2. In the manufacture of tiles, the mold-plate 120 having depressions for forming the flanges with extensions on the upper and lower faces to overlap each other, substantially as and for the purpose set forth

3. In a mold for manufacturing tiles, the 125 depressions *c d* for forming the flanges with their side extensions, and the semicircular holes with enlargement for the nails or screws, substantially as specified.

4. A mold for manufacturing tiles, having 130 one or more transverse curves or angles on its face and the upper and lower ends made cup shape in reverse directions, substantially as and for the purpose set forth.

5. A mold for manufacturing tiles, having one or more transverse curves or angles on its face, the upper and lower ends made cup shape in reverse directions, and the depressions or recesses in the sides for forming the flanges and their extensions, substantially as described.

6. In a mold for manufacturing tiles, the plunger provided with angled or counter corrugation, in combination with the base and plunger of a mold, substantially as shown and specified.

7. In a mold for manufacturing tiles, the plunger provided with one or more transverse curves or angles to coincide with those of the base and top ring of the mold, substantially as shown and set forth.

8. In a mold for manufacturing tiles, the plunger having counter-corrugations and one or more transverse curves or angles, in combination with the base, having perpendicular corrugations, and the top ring, all arranged as shown, and for the purpose specified.

In testimony whereof we affix our signatures in presence of witnesses.
